Patented Nov. 18, 1975

237,745

MANUALLY OPERATED PRESS FOR HEAT SEALING ARTICLES

Joseph E. Pierce, Allentown, Pa., assignor to Compacting
Press Corporation, Bethlehem, Pa.

Filed Oct. 7, 1974, Ser. No. 512,700

Term of patent 14 years

Int. Cl. D15—99

U.S. Cl. D63—1

FIG. 1

FIG. 2

FIG. 3

FIG. 4

FIG. 1 is a top, front, left perspective view of a manually operated press for heat sealing articles in accordance with this invention;

FIG. 2 is a top, front, right perspective view thereof;

FIG. 3 is a rear view thereof; and

FIG. 4 is a bottom view thereof.

I claim:

The ornamental design for a manually operated press for heat sealing articles, as shown.
